ASSIGNORS TO INDIANA LAMP COMPANY, OF CONNERSVILLE, INDIANA, A COR-
PORATION.

LAMP CONSTRUCTION.

1,342,426.

Specification of Letters Patent.

Patented June 8, 1920.

Application filed April 7, 1919. Serial No. 288,103.

To all whom it may concern:

Be it known that we, CHARLES L. DE MARTIN and HARRY C. FOSTER, citizens of the United States, and residents of Connersville, county of Fayette, and State of Indiana, have invented a certain new and useful Lamp Construction; and we do hereby declare that the following is a full, clear, and exact description thereof, reference being had to the accompanying drawings, in which like numerals refer to like parts.

This invention relates to a lamp construction, and more particularly to electric head lights or spot lights for automobiles, motor boats and other uses wherein a strongly projected electric light is desired. The particular feature of this invention is the mechanically economical and simple construction of the lamp. This is accomplished by forming the lamp casing and lens retainer of one piece of metal, which extends forwardly and inwardly in front of the lens, so as to permit the use of a single piece stamped finishing rim. To accomplish this result the lens is inserted into the casing through a slot in the upper portion thereof, which slot is then closed by clamping the finishing rim about the periphery of the lamp casing. This construction permits a lamp to be made by the simplest and most economical stamping process.

In the accompanying drawings which are made a part of this application Figure 1 is a central vertical cross section through the lamp. Fig. 2 is a front elevation thereof, with the upper portion broken away. Fig. 3 is an enlarged section taken on the line 3—3 of Fig. 2. Fig. 4 shows a modified form of means for retaining the reflector against the lens.

There is shown herein a lamp having a metal lamp casing 10, which extends continuously inwardly in front of the lens 11 so as to form an inwardly extending flange 12. In the upper portion of said lamp casing there is a slot 13 having the width of the thickness of the lens 11, and which extends half way around the periphery of said casing for permitting the lens 11 to be inserted therethrough into said casing. The reflector 14 is inclosed in the casing 10 in position to abut against the inner surface of the lens 11 so as to exert an outward pressure thereon caused by the screws 15, which screw through the rear of the lamp cas-

ing and engage the resilient plate 16 mounted on the rear of the reflector. The plate 16 is of a resilient material so as to cause said reflector to be spring pressed against said lens. There is a nickled metal ring 17 between the lens 11 and the outer edge of the reflector 14, which has an inner diameter slightly less than the diameter of the outer periphery of said reflector, as shown in Fig. 3. The nickled ring is 65 adapted to finish off the appearance of the reflector of the lamp, protecting its abutting edge from view and causing it to appear to extend behind the lens rim. The split finishing rim 18 is adapted to surround 70 and inclose the flange 12 and outer periphery of the lamp casing, and is provided with a projecting corrugation 19 which may be formed of the strip of metal cut from the outer rim of the lamp casing for inserting 75 the lens. The projection 19 is adapted to engage in the slot 13 so as to aid in holding the lens in position and fill in the slot after the lens is in place. The split rim 18 is secured together by the bolt 20 on the lower 80 portion thereof, and as said bolt draws the ends of the rim together it clamps the flange 12, the lens 11 and the outer periphery of the lamp casing together so as to tighten 85 and strengthen the construction, at the same time giving it the appearance of the common type of lens rim.

The lamp socket 21 extends through the rear of the lamp casing into the reflector for supporting the lamp 22 therein, and is 90 surrounded by a resilient metal housing 24 supporting said socket and for permitting the sliding adjustment thereof.

The modified view shown in Fig. 4 shows another means of forcing the reflector 14 95 against the lens, namely by a single screw 26, which screws through the rear of the lamp casing against the housing 24 mounted on the rear of the reflector, the lamp socket being slidably adjustable in said 100 housing.

The invention claimed is:

1. In a lamp construction having a parabolic lamp casing, a flange integral with and forming a part of said casing extending radially inwardly from the outer periphery thereof and having a semi-circular peripheral slot, a circular lens adapted to be inserted through said slot into said casing so as to lie adjacent said flange, a re- 110

- 5 reflector mounted in said casing and abutting said lens for holding it in position against said flange, means for resiliently and adjustably securing said reflector in position
10 5 for holding said lens, and a resilient rim adapted to be mounted over said flange and the periphery of said casing for inclosing and locking the lens therein.
- 10 2. In a lamp structure having a lamp casing, with a slot extending partially around the periphery thereof, an inwardly extending flange integral with and forming a part of said lamp casing, a lens adapted to be inserted in said casing through the slot
15 15 therein, a reflector abutting said lens, a rim adapted to be mounted over said flange and the periphery of said casing, and a rib on said rim adapted to extend into said slot for closing it after the lens is in place.
- 15 20 3. A lamp structure having a lamp casing with a slot extending partially around the periphery thereof, a lens adapted to be inserted in said casing through the slot therein, a rim adapted to be mounted over
25 25 said casing and lens, and a rib on said rim adapted to extend into said slot for closing it after the lens is in place.
- 20 4. In a lamp structure having a lamp casing with a slot extending partially around the periphery thereof, an inwardly extending flange integral with and forming a part of said lamp casing, a lens adapted to be inserted in said casing through the slot therein, a reflector adapted to abut said
30 30 lens, a resilient plate on said reflector, means on said casing for engaging said plate and forcing said reflector and lens outwardly, and a rim adapted to be mounted over said flange and the periphery of said casing for closing said slot and holding said lens in position.
- 30 40 5. In a lamp structure having a lamp casing with a slot extending partially around the periphery thereof, an outwardly extending flange integral with and forming a part of said lamp casing, a lens adapted to be inserted in said casing through the slot therein, a reflector adapted to abut said lens, a resilient plate on said reflector, means on said casing for engaging said resilient plate and forcing said reflector and lens outwardly, a rim adapted to be mounted over said flange and the periphery of said casing, and a rib on said rim adapted to extend into said slot for closing it after the lens is in place.
- 35 45 6. In a lamp structure having a lamp casing, a lens mounted in the front of said casing, a reflector within said casing adapted to abut against said lens, a resilient plate mounted on the rear of said reflector, and adjustable means on said casing actuated from the exterior thereof for engaging said plate so as to resiliently force said reflector against said lens.
- 45 60 In witness whereof, we have hereunto affixed our signatures.

CHARLES L. DE MARTIN.
